Inventor

William E. Knox

By Grace C. Knobell

Attorney

UNITED STATES PATENT OFFICE.

WILLIAM E. KNOX, OF MIAMI, FLORIDA.

RAILWAY TIE PLATE.

Application filed July 11, 1922. Serial No. 574,274.

To all whom it may concern:

Be it known that I, WILLIAM E. KNOX, a citizen of the United States, residing at Miami, in the county of Dade, State of Florida, have invented certain new and useful Improvements in Railway Tie Plates; and I do hereby declare the following to be a full, clear, and exact description of the invention, such as will enable others skilled in the art to which it appertains to make and use the same.

This invention relates to new and useful improvements in railway rail fastening devices, and particularly to devices for holding rails on ties.

One object of the invention is to provide a device of this character which is simple in construction, cheap to manufacture, and which will effectively maintain the rail and spike against any movement.

Another object is to provide a device of this character which is so constructed that rails of different widths may be readily accommodated, and the spikes effectively held against working out of the ties.

Other objects and advantages will be apparent from the following description when taken in connection with the accompanying drawing.

30 In the drawing:

Figure 1 is a top plan view of a rail and a portion of a tie, showing the invention applied thereto.

Figure 2 is a transverse sectional view 35 through the rail, showing the invention in end elevation.

Figure 3 is a side elevation of the rail and the invention applied thereto.

Figure 4 is a plan view of the blank from 40 which the device is formed.

Referring particularly to the accompanying drawing, 10 represents a portion of a railway tie, and 11 a portion of a rail disposed thereon, and in connection with which the present invention is used.

Disposed on the tie, beneath the rail, and on which the rail rests, is a metal plate 12, the opposite ends of which project beyond the sides of the base flange of the rail, as 50 clearly seen in the plan and sectional view. Formed on one end of the plate 12 are the tongues 13, which are bent upwardly and

inwardly, to lie on the heads of the spikes 14, so that the spikes will be prevented from becoming loose with respect to the tie. 55

In the opposite end of the plate 12 there are formed two inwardly extending parallel cuts 15, resulting in the tongue 16, said tongue, however, being considerably longer than the cuts, in view of the fact that said 60 end of the plate had been cut transversely, from its ends, to the said cuts. This tongue 16 is bendable to extend upwardly and inwardly, on the head of a spike 17, and with its terminal lying against the side face of 65 the web of the rail. Formed longitudinally in the intermediate portion of the tongue 16, or that portion which is arranged to be bent, is a slot 18 of a width to receive the shank of the spike 17 therethrough. 70

Attention is called to the fact that the slot 18 is of sufficient length to permit the insertion of the spike 17, whether the rail base is wide or narrow, the latter case permitting the spike to lie in the inner portion of the slot, so that the portions 18', at the sides of the slot, will partially embrace the rear of the head of the spike. In the former case the spike 17 will lie in the outer portion of the slot 18, so that the portion, 75 80 outwardly of the outer end of the slot, will embrace and overlie the head of the spike. Thus rails of different widths may be readily accommodated and the spikes held against movement relative to the tie. 85

As seen in Figure 4, the cuts 15 of the plate, are wide, and narrow portions of the plate removed from opposite sides of the tongue 16. This permits ready access to the tongue for bending the same upwardly and 90 inwardly over the head of the spike 17.

What is claimed is:

1. A rail fastener comprising a plate having spike engaging bendable tongues on one end and a bendable spike engaging tongue 95 on the other end, the bendable portion of the said tongue being longitudinally slotted for the reception of the shank of a spike.

2. A rail fastener comprising a plate having tongues extending from one end and 100 bendable to overlie the heads of spikes, the opposite end of the plate being inwardly cut to produce a bendable tongue, the tongue being longitudinally slotted at the bendable

portion thereof whereby rails of different widths will be received and spikes properly engageable in the slot.

3. A rail fastener comprising a plate having tongues extending from one end thereof, the opposite end of the plate being inwardly cut on parallel lines with a resultant intermediate tongue, said tongue extending beyond the said end of the plate

and being longitudinally slotted in its portion inwardly of the end of the plate.

In testimony whereof, I affix my signature, in the presence of two witnesses.

WILLIAM E. KNOX.
